Attorney

UNITED STATES PATENT OFFICE.

CALVIN F. WILEY, OF COLUMBUS, OHIO.

ASH-SIFTING SHOVEL.

1,277,279.

Specification of Letters Patent. Patented Aug. 27, 1918.

Application filed July 5, 1917. Serial No. 178,716.

To all whom it may concern:

Be it known that I, CALVIN F. WILEY, a citizen of the United States, and resident of Columbus, in the county of Franklin and State of Ohio, have invented certain new and useful Improvements in Ash-Sifting Shovels, of which the following is a specification.

This invention relates to improvements in shovels; the dominant object of the invention being to provide an ash sifting shovel whereby ashes can be gathered and sifted, thus, retaining such fuel as may be therein and discharging the waste from the same.

Among other aims and objects of the invention may be recited, the provision of a shovel of the character mentioned with a view to compactness, and in which the number of parts are few, the construction simple, the cost of production small, and efficiency and operation high.

The improvements in the details and arrangements of parts will be apparent from an inspection of the accompanying drawings, in connection with the specific description hereinafter contained, and wherein the preferred embodiment of the invention is disclosed for the purpose of imparting a full understanding of the same.

In the drawings:

Figure 1 is a top plan of the improved shovel; and

Fig. 2 is a longitudinal section therethrough.

Having more particular reference to the drawings, and in connection with which like reference characters will refer to corresponding parts, the improved shovel comprises a frame designated in its entirety by the numeral 1 and comprising side and center stays and an end stay, this stay serving as the forward edge of the shovel. It is to be noted in this connection, that the various stays from which the frame is formed are so bent as to constitute the usual scooped shaped shovel, the rear end thereof being so arranged as to provide an efficient socket for receiving a handle 2 therein, the handle in turn being secured to the same by fastening bolts or other suitable fastenings therethrough.

Over the frame 1 and clamped between the side and end stays thereof which are formed of channeled metal, is a coarse mesh

screen 3, the rear portion being crimped as 55 at 4 in order that it will conform to the curvature of the rear portions of the various stays. The center stay of the frame not only serves as means for supporting the intermediate portion of the wire mesh 3 but also as 60 an efficient skid and protector therefor, thus, allowing the shovel to be readily engaged with ashes or other matter.

In operation, the shovel is moved into engagement with the ashes arranged in the 65 pit of a furnace and with the same arranged thereon is vibrated to cause the sifting of the waste therefrom through the screen 3 and the retaining of such fuel as may be in the ashes upon the shovel. After the 70 sifting operation, the cinders may be readily discharged from the shovel into a bin or other receptacle. It will be understood that by sifting the ashes in the pit of a furnace all dust incident to such operation will be 75 eliminated, inasmuch as the same will be taken off by way of the flue of the furnace. In this way, the operation is rendered clean and agreeable.

Manifestly, the construction shown is 80 capable of considerable modification and such modification as is within the scope of my claims, I consider within the spirit of my invention.

I claim:

1. A shovel comprising a foraminated body portion, channeled metal side strips engaging the side edges thereof, a channeled metal end strip extending across the front edge of the same, and a center stay extending longitudinally beneath the body of the shovel.

2. A shovel comprising a foraminated body portion, channeled metal side strips engaging the side edges thereof, the rear 95 ends of said strips projecting centrally from the rear edge of the body in parallel spaced relation and having oppositely curved faces adapted to receive a handle therebetween, a channeled metal end strip extending across the front edge of the body, and a longitudinally extending center stay disposed beneath the body of the shovel having its rear end connected with the handle, and its front end with the front end strip of the shovel.

In testimony whereof I affix my signature hereto.

CALVIN F. WILEY.
